SELECTIVE DUPLICATING MACHINE

William H. Uhl, Penfield, N. Y., assignor to Commercial Controls Corporation, Rochester, N. Y.

Application April 13, 1950, Serial No. 155,611

13 Claims. (Cl. 101—90)

1 This invention relates to a printing machine and more particularly to a machine for repeatedly printing a line of type upon a card or other medium.

Briefly, the machine includes a framework, generally indicated at 10, on which is mounted a carriage, generally indicated at 12. Carriage 12 is mounted for longitudinal movement with respect to framework 10 and carries a platen, generally indicated at 14 (Figure 5), which is driven as the carriage is moved longitudinally with respect to framework 10. The platen shaft 16 (Figures 5 and 6) is operably connected by the mechanism, generally indicated at 18 (Figure 1), to the shaft 20 carrying a plurality of settable type wheels, generally indicated at 22 (Figure 6). As the carriage is moved longitudinally of framework 10, the type wheels are actuated by shaft 20 so that the line of type selected engages one of the raised portions on platen 14 (Figure 10) and prints with a rolling action. After printing has taken place, the shaft 20 carrying the type wheels is turned in the opposite direction by the mechanism 18 so that the line of type selected is moved forwardly to a position from which it moves rearwardly and again prints with a rolling action by coaction with the next raised portion on platen 14 (Figure 10).

One of the objects of this invention is to provide a printing machine which will be simple, practical and thoroughly durable. Another object is to provide a machine of the above character which may be manufactured from inexpensive materials without undue labor cost. Another object is to provide a machine of the above character which will be strong and durable and well able to withstand the strain of continuous hard usage. Another object is to provide a machine of the above character which will be efficient and accurate in operation. A further object is to provide a machine of the above character which will successively print a selected line of type upon a card or other medium not held by or connected to the machine. Still another object is to provide a machine of the above character in which a selected line of type and the platen are actuated so that printing is effected with a rolling action during each successive printing operation.

The invention accordingly consists in the features of construction, combinations of elements, and arrangements of parts, as will be exemplified in the structure to be hereinafter described, and the scope of the application of which will be indicated in the following claims.

2 Referring now to the drawings, in which is shown one of the various possible embodiments of this invention;

Figure 1 is a front elevation of the machine, certain portions being broken away for purposes of illustration;

Figure 2 is a rear elevation of the machine, certain portions being broken away for purposes of illustration;

Figure 3 is a top plan of the machine shown in Figures 1 and 2 on an enlarged scale, certain portions being broken away for purposes of illustration;

Figure 4 is a longitudinal vertical section taken on the line 4—4 of Figure 3;

Figure 5 is a vertical transverse section taken on the line 5—5 of Figure 1;

Figure 6 is a vertical transverse section taken on the line 6—6 of Figure 1;

Figure 7 is a vertical section taken on the line 7—7 of Figure 3;

Figure 8 is a section similar to Figure 7 with the parts in different relative positions;

Figure 9 is a vertical section on an enlarged scale taken on the line 9—9 of Figure 6; and

Figures 10—13 diagrammatically illustrate the operation of certain parts of the machine, these parts being shown in different relative positions in each figure.

Similar reference characters refer to similar parts throughout the several views of the drawing.

Referring now to Figures 1 and 5, the framework 10 includes two pairs of rails 24, 26, 28 and 30 which are held in spaced relationship with respect to each other by side plates 32 and 36. To hold the rails and side plates in assembled relationship, screws 34 and 38 (Figures 1 and 2) extend through the side plates 32 and 36 and rails 24, 26, 28 and 30, and thread into threaded holes in the ends of rods 40 and 41 (Figures 3, 4 and 5).

Adjacent the ends of side plates 32 and 36 are two pairs of vertical supports 42, 44, 46 and 48 (Figures 1, 2 and 3). Supports 42, 44, 46 and 48 serve to hold a pair of rotatably mounted rods 50 and 52 on which the inking ribbon 54 is mounted. Rods 50 and 52 are provided with knobs 56 and 58, by means of which the rods 50 and 52 may be turned to wind the ribbon from one rod to another and thus change the ribbon when it becomes worn. Springs 57 are provided to provide friction which holds knobs 56 and 58 in the positions in which they are set.

The carriage 12 includes a base, generally indicated at 64 (Figure 5), which is channel-

shaped in cross section. Four rollers 66, 68, 70 and 72 (Figures 3 and 4) are mounted on the legs 64a and 64b of base 64 (Figure 5) and are positioned between the rails 24, 26, 28 and 30. Rail 30 is provided with a groove 74 in which rollers 66 and 68 (Figure 4) ride, thus preventing the rollers from moving transversely of the rails. Thus, base 64 is mounted on rails 24, 26, 28 and 30 by rollers 66, 68, 70 and 72 so that it may be moved longitudinally of the rails. Rods 41 (Figure 4) at the ends of the rails limit longitudinal movement of base 64 and thus carriage 12 with respect to the machine's framework 10.

The printing mechanism is mounted upon a pair of side plates 76 and 78 (Figures 1, 2 and 5), which are connected to base 64 by means of bolts 80 (Figure 5). Side plates 76 and 78 are held in spaced relationship with respect to each other by means of rods 82 and 84 (Figures 3 and 5), which are connected to plates 76 and 78 by means of screws 86 (Figure 2) and 88 (Figure 1).

Platen 14 (Figure 6) is mounted on shaft 16, which is rotatably mounted on a pair of bearing members 90 and 92 mounted on side plates 76 and 78. When the carriage 12 is moved to the left, as viewed in Figure 1, shaft 16 is driven by mechanism actuated by a rack 60 (Figures 2, 3 and 6), which is mounted on supports 42 and 46 by bolts 62. This mechanism includes a gear 94 (Figures 3, 5 and 6) mounted on and secured to a sleeve 96 which is rotatably mounted on shaft 16. Sleeve 96 is maintained in spaced relationship with respect to bearing 92 by means of a collar 98. A disc 100 (Figures 2 and 6) is mounted on and secured to the outer end of sleeve 96 and carries a pawl 102. Pawl 102 is pivotally mounted on a pivot pin 104 and is resiliently pressed into engagement with a ratchet wheel 106 by means of spring 108. Ratchet wheel 106 is mounted on and secured to a sleeve 110 which is connected to shaft 16 by means of set screw 112.

When the carriage 12 is moved to the right, as viewed in Figure 2, rack 60 drives gear 94 and thus disc 100 in a clockwise direction. When disc 100 is turned in a clockwise direction, pawl 102 engages ratchet wheel 106 and turns it in the same direction. When carriage 12 is moved from the right-hand end of the rack 60, as viewed in Figure 2, to the left-hand end thereof, gear 94 and thus disc 100 turn in a counterclockwise direction. At this time, pawl 102 ratchets over ratchet wheel 106, and thus shaft 16 is not driven.

Platen 14 (Figure 6), which is made of rubber or similar material, preferably is mounted on a sleeve 114, which is connected to shaft 16 by means of set screw 116. Platen 14 is bonded to sleeve 114, and thus as shaft 16 turns, platen 14 is turned with it. Platen 14 has a plurality of 60 equidistantly spaced raised portions 118 (Figures 4 and 5) formed on its external surface which are parallel to the longitudinal axis of the platen. It should be noted that the space between each adjacent pair of raised portions is flattened.

The type wheels 22 are mounted beneath platen 14 on a shaft 20 (Figure 6), which is rotatably mounted on bearings 124 and 122 mounted on plates 76 and 78. Movement of shaft 20 70 to the right with respect to bearing 122 is prevented by means of a snap ring 125 which is mounted in a groove 126. The type wheels are all similar in construction to type wheel 22a (Figure 4). Type wheel 22a is ring shaped and

5 rotatably mounted on a sleeve 128 (Figures 4 and 6) mounted on shaft 20. Type wheel 22a (Figure 4) is provided with a plurality of teeth 22b, each of which carries a digit in raised type thereon.

Type wheels 22 are prevented from moving longitudinally with respect to sleeve 128 by the hub portions 130a and 132a of a pair of arms 130 and 132 (Figures 6 and 9) connected to shaft 20 by set screws 134 and 136. The lower ends 15 of arms 130 and 132 are connected by means of a rod 138 and with rod 138 form a support for a locking bar 140 which locks the type wheels in their selected positions. Bar 140 includes a pair of tongue portions 140a and 140b, which extend through slots 130b and 132b in arms 130 and 132 and which are connected to the hub portions of arms 130 and 132 by means of springs 142 and 144. These springs resiliently hold locking bar 140 in engagement with the notches 25 between the raised teeth on the type wheels 22 and thus hold them in set positions. When it is desired to reset the type wheels, the carriage 20 is moved to the left-hand end of the machine, as viewed in Figure 1, locking bar 140 is moved downwardly out of engagement with the type wheels, and the type wheels are reset with a stylus. When the type wheels have been reset 30 and properly aligned, locking bar 140 is released and it locks the type wheels in their set positions.

As pointed out hereinabove, when the carriage 12 (Figure 1) is moved to the left, as viewed in this figure, shaft 16 is turned in a counterclockwise direction. Shaft 16 has an actuator 35 146 (Figure 6) mounted on its right-hand end, the hub portion 146a of which is connected to shaft 16 by set screw 148. As will be pointed out hereinafter, actuator 146 acts through a pair of cams 150 and 152 (Figures 1 and 7), which are operably connected by gears 154 and 156 (Figures 1 and 3) to move the type wheels through a printing cycle as carriage 12 is moved longitudinally of the machine. The motion imparted to the type wheels is such that each time the selected line of type is printed, printing is effected by a coordinated rolling action between the platen and line of type.

Cam 150 (Figures 6 and 7) is mounted on and secured to a sleeve 158, which is connected to shaft 20 by a set screw 160. It will be noted by referring to Figure 6 that cam 150 lies in the same plane as actuator 146. Gear 156, which is also mounted on and secured to sleeve 158, meshes with a gear 156 (Figures 1 and 3), which is mounted on and secured to a sleeve 162. Sleeve 162 is rotatably mounted on a stud shaft 164 secured to and extending outwardly from side plate 76. Cam 152 (Figure 3) is also mounted on and secured to sleeve 162 and lies in the same plane as cam 154 (Figure 3) and actuator 146 (Figure 5). Referring to Figure 3, it will be noted that sleeve 162 is held in position on stud shaft 164 by means of collar 166 and snap ring 168.

Referring now to Figure 10, the platen 14 is illustrated in the position it occupies at the beginning of a printing operation. The right-hand edges (Figure 10) of the row 22c of type to be printed and the raised portion 14a of the platen are in printing position with respect to each other. As platen 14 is turned by shaft 16 in a counterclockwise direction, actuator 146 also is turned by shaft 16. Actuator 146 acts through the surface 146a on one of its teeth against surface 150a on cam 150 to turn cam 150 in a clock- 75

wise direction. Because the cam 150 is operationally connected to gear 154, gear 154 is also turned in a clockwise direction. Gear 154 acts through gear 156 to turn cam 152 in a counterclockwise direction. As shaft 16 continues to turn in a counterclockwise direction, the line of type 22c (Figure 11) prints with a rolling action upon the card as it presses the ribbon and card against the raised portion 14a of platen 14. As printing takes place, cam 158 (Figure 8) is turned in a clockwise direction and cam 152 in a counterclockwise direction. When printing has been completed, as shown in Figure 11, the surface 146a of actuator 146 has moved out of engagement with surface 150a of cam 150, and the surface 146b of another tooth of actuator 146 engages surface 152a of cam 152. Actuator 146 acts through surface 146b to turn cam 152 in a clockwise direction. This motion is transmitted through gear 156 to gear 154, which turns shaft 20 and thus type wheel 22a in a counterclockwise direction.

Referring to Figure 12, it will be noted that while actuator 146 is acting through cam 152 to move type wheels 22 in a counterclockwise direction, platen 14 continues to turn in a counterclockwise direction. Thus, as line of type 22c is being moved back to printing position, the flat surface 14c between raised portions 14a and 14b is positioned opposite the line of type 22c. Thus the movement of line of type 22c back into printing position cannot move the card being printed upon into engagement with platen 14. As is shown in Figure 13, platen 14 continues to turn in a counterclockwise direction and type wheels 22 in a clockwise direction until the type wheels reach printing position and the raised portion 14b on platen 14 is positioned slightly to the left of printing position with respect to the selected line of type 22c. At this time, it will be noted that the actuator is not in engagement with either cam 150 or 152. Further movement of shaft 16 in a counterclockwise direction causes raised portion 14b on platen 14 to press the card or medium being printed upon into engagement with the right-hand edge of the line of type 22c. At this time, surface 146c of another tooth on actuator 146 engages surface 150a on cam 150 and another line of type is again printed on the card being printed upon.

It will be noted that to turn shaft 16 carriage 12 (Figure 1) must be moved longitudinally of the machine. Thus, the lines of type are spaced on the card being printed upon as the card remains stationary with respect to the machine. The card is not moved during printing because printing is effected with a rolling action.

In operation, type wheels 22 (Figure 6) are first set so that the desired line of type is positioned in printing position. To accomplish this, the carriage 12 is moved to the left-hand end of the machine, as viewed in Figure 1, and locking bar 149 is pulled downwardly (Figure 6). This permits the type wheels to be rotated with a stylus until they are correctly set. The locking bar is then released and carriage 12 is moved to the right-hand end of the machine, as viewed in Figure 1. A card 170 (Figure 4) is next placed upon the ribbon 54, as viewed in Figures 3 and 4, to the left of platen 14, and carriage 12 is moved to the left-hand end of the machine, as viewed in Figure 1.

As carriage 12 moves to the left, rack 60 (Figure 3) acts through gear 94 to turn disc 100 in a clockwise direction, as viewed in Figure 2. 75

As disc 100 turns, it acts through pawl 102 and ratchet wheel 106 to turn shaft 16 in a clockwise direction (Figure 2). As shaft 16 turns, it drives actuator 146 (Figure 1), which acts upon cam 150 (Figure 10) to cause the line of type 22c to coact with raised portion 14a on platen 14 and print upon card 170 (Figure 4). After printing has been effected, the actuator acts upon cam 152 (Figure 11), which acts in turn through gears 156 and 154 to turn shaft 20 and thus the line of type 22c back into printing position. Further movement of carriage 12 along rack 60 (Figure 3) acts through the same mechanism to cause another printing operation.

15 Each time printing is effected with a rolling action so that the card being printed upon is not moved longitudinally with respect to the machine. Furthermore, as carriage 12 moves longitudinally of the machine, the line of type 22c is 20 successively printed so that the same line of type appears a number of times upon the card, each line of type being equidistantly spaced with those adjacent to it. When the carriage 12 reaches the machine's left-hand end, as viewed in Figure 25 1, it is moved back to the right-hand end and the card 170 removed. During movement of the machine in this direction, pawl 102 ratchets around ratchet wheel 106 (Figure 2), and thus the printing mechanism is not actuated.

30 It will thus be seen that a simple, practical and thoroughly efficient machine has been described. It is not necessary in this machine to have the card or other medium being printed upon secured to the machine, as printing is effected with a 35 rolling action so that the card is not moved with respect to the machine during the printing operation. This machine is of simple construction and is so designed that it may be easily operated by an inexperienced person. Furthermore, it 40 will be noted that the several objects hereinabove mentioned, as well as many others, have been successfully accomplished.

45 As many possible embodiments may be made of the mechanical features of the above invention, and as the art herein described might be varied in various parts, all without departing from the scope of the invention, it is to be understood that all matter hereinabove set forth, or shown in the accompanying drawings, is to be interpreted as 50 illustrative and not in a limiting sense.

What is claimed is:

1. In a printing machine, in combination, a supporting member, a platen mounted on said supporting member, means rotatably mounting said platen, said platen having a plurality of raised ridges thereon, said ridges being parallel to the axis of rotation of said platen, a line of type, means mounting said line of type for rocking movement with respect to said platen, the axis about which said line of type rocks being parallel to the axis of said platen, means for rotating said platen, and means operably connecting said platen and said line of type, said last-mentioned means including mechanism for moving said line of type in a direction to effect printing by coaction between said line of type and one of said ridges on a card positioned between said platen and said line of type and mechanism for moving said line of type in the opposite direction until it is aligned with the next ridge on said platen between successive printing operations.
2. In a printing machine, in combination, a supporting member, a shaft mounted on said supporting member, a platen mounted on said

shaft, a line of type, means mounting said line of type on said supporting member for rocking movement with respect to said platen, said line of type being longitudinally aligned with the axis of said shaft, cam means operatively connected to said line of type, means on said shaft for actuating said cam means when said shaft is turned to move said line of type through printing position with respect to said platen, and secondary cam means operatively connected to said line of type, said secondary cam means being actuated by means on said shaft and being actuated by said means to turn said line of type in the opposite direction from said first-mentioned cam means, whereby said line of type is returned to printing position by said second-mentioned cam means after each printing operation is completed.

3. In a printing machine, in combination, a supporting member, a platen mounted on said supporting member, means rotatably mounting said platen on said supporting member, said platen having a plurality of raised portions thereon parallel to its axis of rotation, a shaft, a line of type wheels rotatably mounted on said shaft, said type wheels each having a plurality of characters thereon and being adjustable, means for locking said type wheels in adjusted positions to said shaft, the line of type selected being parallel to the axis about which said platen rotates, means for rotating said platen, means operatively connecting said platen to said shaft, said means including mechanism for moving said line of type into printing engagement with one of the raised portions on said platen to effect printing on a card positioned between said platen and the line of selected type, and mechanism for moving said line of selected type in the opposite direction after each printing operation until it is aligned with the next raised portion on said platen.

4. In a printing machine, in combination, a framework, a carriage, means mounting said carriage for movement longitudinally with respect to said framework, a platen mounted on said carriage, means for rotating said platen as said carriage moves longitudinally of said framework, type means, means mounting said type means for rocking movement with respect to said platen, said platen having a plurality of raised portions thereon which coact with said type means to effect printing, means for moving said type means in a direction to effect printing as said carriage moves longitudinally of said framework, and means for moving said line of type in the opposite direction during the period between successive printing operations as said carriage continues to move.

5. In a printing machine, in combination, a supporting member, a platen rotatably mounted on said supporting member, means mounting said platen for movement longitudinally with respect to said supporting member, the axis of rotation of said platen extending transversely across said supporting member, means for rotating said platen as said platen is moved longitudinally with respect to said supporting member, a line of type extending transversely across said supporting member, means mounting said line of type for rocking movement with respect to said platen, and means operatively connecting said platen rotating means and said line of type mounting means, said last-mentioned means driving said line of type with a rocking motion into and out of engagement with said platen, as

said platen moves longitudinally with respect to said supporting member.

6. In a printing machine, in combination, a supporting member, a platen rotatably mounted on said supporting member, means mounting said platen for movement longitudinally of said supporting member, the axis of rotation of said platen extending transversely across said supporting member, said platen having a plurality of ridges formed thereon parallel to the axis thereof, means for rotating said platen as said platen is moved longitudinally of said supporting member, type means, means mounting said type means for rocking movement with respect to said platen, and means operatively connecting said platen rotating means and said last-mentioned means, said connecting means driving said type means with a rocking motion toward a ridge on said platen during the printing portion of the operating cycle and in the opposite direction between said ridge and the next succeeding ridge on said platen during the remaining portion of the operating cycle, as said platen moves longitudinally of said supporting member.

7. In a printing machine, in combination, a framework, a carriage, means mounting said carriage for movement longitudinally with respect to said framework, a platen mounted on said carriage, means engaging said framework for rotating said platen as said carriage is moved longitudinally with respect to said framework, a shaft, settable type wheels mounted on said shaft, each type wheel having a number of characters thereon, means for locking said type wheels in adjusted position with respect to said shaft, and means operatively connecting said platen and said shaft to cause said type wheels to reversably rotate into and out of printing position with respect to said platen as said carriage is moved longitudinally with respect to said framework.

8. In a printing machine, in combination, a framework, a carriage mounted for movement longitudinally of said framework, a shaft mounted on said carriage, a platen mounted on said shaft, means for driving said shaft as said carriage is moved longitudinally of said framework, the axis of rotation of said platen extending transversely across said carriage, said platen having a plurality of ridges thereon extending longitudinally thereof, a second shaft mounted on said carriage, settable type wheels mounted on said shaft, each type wheel having a number of characters thereon, means for locking said type wheels in set position to said second shaft, cam means mounted on said second shaft, driving means on said first shaft for driving said cam means to move the line of selected type through a printing operation with respect to one of the ridges on said platen, secondary cam means, and means operatively connecting said secondary cam means to said second shaft, said driving means on said first shaft after the completion of each printing operation acting through said secondary cam means to move said line of type backwardly until it is aligned with the next ridge on said platen after each printing operation.

9. In a printing machine, in combination, a framework, a carriage, a platen rotatably mounted on said carriage, means mounting said carriage for movement longitudinally of said framework, the axis of rotation of said platen extending transversely across said carriage, said platen having a plurality of ridges thereon extending peripherally parallel to the rotational axis thereof, a rack on said framework, a gear mounted on said car-

riage, clutch means positioned between said platen and said gear, said rack driving said platen through said gear and said clutch means when said carriage is moved in one direction, a shaft rockably mounted on said carriage, settable type wheels mounted on said shaft, each type wheel having a number of characters thereon, and means for rocking said shaft while said platen rotates, whereby the line of selected type moves against and in the same direction as a ridge on said platen during the printing portion of the operating cycle, and in the opposite direction toward the next succeeding ridge on said platen during the remaining portion of the operating cycle.

10. A printing machine comprising, in combination, a framework, a carriage mounted for movement longitudinally of said framework, a shaft mounted transversally on said carriage, means for driving said shaft as said carriage is moved longitudinally of said framework, a platen mounted on said shaft, said platen having a plurality of ridges thereon extending longitudinally thereof, type means, means rockably mounting said type means on said carriage below said platen, means operatively connecting said shaft and said type mounting means to rock said type means into engagement with successive ridges on said platen as said platen rotates, and an inking ribbon longitudinally disposed on said framework and extending between said platen and type means, whereby a card or the like may be placed on said ribbon to be printed by said type means when said carriage is moved longitudinally of said framework.

11. A printing machine comprising, in combination, a framework, a carriage mounted for movement longitudinally of said framework, a shaft mounted transversally on said carriage, a rack on said framework, a gear rotatably mounted on said shaft and engageable with said rack, clutch means associated with said gear whereby said shaft is driven from said rack when said carriage is moved in one direction, a platen mounted on said shaft and having a plurality of ridges thereon extending longitudinally thereof, type means, means rockably mounting said type means on said carriage below said platen, means operatively connecting said shaft and said type mounting means to rock said type means into engagement with successive ridges on said platen as said platen rotates, and an inking ribbon longitudinally disposed on said framework and extending between said platen and type means, whereby a card or the like may be placed on said ribbon to be printed by said type means when said carriage is moved longitudinally of said framework.

12. A printing machine comprising, in combination, a framework, a carriage mounted for movement longitudinally of said framework, a shaft mounted transversally on said carriage, a rack on said framework, a gear rotatably mounted on said shaft and engageable with said rack, clutch means associated with said gear whereby said shaft is driven from said rack when said

carriage is moved in one direction, a platen mounted on said shaft and having a plurality of ridges thereon extending longitudinally thereof, a second shaft rockably mounted on said carriage below said platen, settable type wheels mounted on said second shaft, each type wheel having a number of characters thereon, means locking said type wheels in set position to said second shaft, a cam mounted on said second shaft, means on said first shaft driving said cam to move the line of selected type through a printing operation with respect to one of the ridges on said platen, a secondary cam, means operatively connecting said secondary cam to said second shaft, said driving means on said first shaft acting through said secondary cam after completion of each printing operation to move said line of selected type backwardly until it is aligned with the next ridge on said platen after each printing operation, and an inking ribbon longitudinally disposed on said framework and extending between said platen and type wheels, whereby a card and the like may be placed on said ribbon and be printed repeatedly by said line of selected type when said carriage is moved in said one direction.

13. In a printing machine, in combination, a longitudinal supporting frame, a carriage mounted for slidable movement along said frame, a rack secured to said frame, means for mounting a card on said frame, means for supporting an inking ribbon on said frame, said ribbon and said card being mounted in superimposed relation, a platen roller rotatably secured to said carriage above said ribbon, type supporting mechanism secured to said carriage below said ribbon and in alignment with said platen, and gearing mechanism meshing with said rack and interconnected with said type supporting mechanism to move said type supporting mechanism in one direction into printing position beneath said platen upon longitudinal movement of said carriage with respect to said support to print on said card and to move said type supporting mechanism in the other direction out of printing position as said carriage continues to move in the same direction whereby successive imprints are made on said card as said carriage slides along said frame.

WILLIAM H. UHL.
